UNITED STATES PATENT OFFICE

166,390

TOP AND BACKSPLASHER UNIT FOR
ELECTRIC RANGE

Lurelle Guild, Noroton, Conn., and Frederick W. Perl, Mansfield, Ohio, assignors to Westinghouse Electric Corporation, a corporation of Pennsylvania

Application April 6, 1951, Serial No. 14,732

Term of patent 14 years

(Cl. D81—25)

To all whom it may concern:

Be it known that we, Lurelle Guild and Frederick W. Perl, citizens of the United States, residing at Noroton, in the county of Fairfield and State of Connecticut, and at Mansfield, in the county of Richland and State of Ohio, respectively, have invented a new, original, and ornamental Design for a Top and Backsplasher Unit for Electric Range, of which the following is a specification, reference being had to the accompanying drawing, forming a part thereof.

In the drawing:

Fig. 1 is a perspective view of a top and backsplasher unit for electric range showing our new design;

Fig. 2 is a side elevational view thereof;

Fig. 3 is a fragmentary perspective view thereof, taken on a larger scale; and

Fig. 4 is a sectional view on the same scale as Fig. 3 taken on line IV—IV of Fig. 1.

The dominant features of our design reside in the portions shown in full lines.

We claim:

The ornamental design for a top and backsplasher unit for electric range, substantially as shown and described.

LURELLE GUILD.
FREDERICK W. PERL.
